Patented Apr. 12, 1927.

UNITED STATES PATENT OFFICE.

NORMAN MARSHALL, OF NASHUA, NEW HAMPSHIRE, ASSIGNOR TO REMINGTON ARMS COMPANY, INC., A CORPORATION OF DELAWARE.

TUBE POLISHING OR SIZING MACHINE.

Application filed February 26, 1924. Serial No. 695,249.

The invention relates to a machine for polishing or for polishing and sizing paper, fibre and other non-metallic tubes to perfect their shape or to polish their outer surface.

5 Machines heretofore in use for this purpose have not proved wholly satisfactory by reason of their limited production, as well as by reason of the more or less frequent crumpling or splitting of tubes due to their sticking 10 in the shaping and polishing die or the burning or blistering of tubes by reason of the frictional heat developed between the die and surface of the tubes.

It is the object of the present invention to 15 provide a machine having a high production and operating to efficiently and uniformly size or polish the tubes without danger of injury thereto. To these ends the invention comprises the features of construction and 20 combinations of parts hereinafter described and set forth in the claims.

A machine embodying the invention is shown in the drawings in which Figure 1 is a side elevation; Fig. 2 a plan view; Figs. 3 25 and 4 details of the tube carrying mandrel; Figs. 5 and 6 sectional detail views of the mandrel and shaping and polishing die; Fig. 7 an end view of the machine looking toward the right in Fig. 1; Fig. 8 a sectional view on line 8-8, Fig. 1; and Fig. 9 a partial side elevation similar to Fig. 1 showing a modified form of tube lubricating means.

The machine shown in the drawings comprises generally a reciprocating and intermittently indexed turret provided with two tube mandrels, a revolving die through which a tube is forced by one mandrel during the reciprocation of the turret, a tube support or feeder from which the other mandrel takes a tube during the same reciprocation of the turret, and means for applying a lubricant to each tube before it enters the die. Indexing movements are given to the turret while the mandrel is withdrawn from the die to move each mandrel successively from tube receiving position to position to enter the die and then again into tube receiving position. The tube passed through the die is stripped from the mandrel during its return stroke and the finished tubes pass through a delivery tube from which they may be delivered in succession onto a carrier or into a receiver.

As shown, the turret 2 is provided with 55 two tube carrying mandrels 4 and is mount-

ed in a slide 6. The slide is mounted in guideways 8 and is connected by a link 10 with the upper end of an actuating lever 12. The lever is oscillated by a crank 14 carried by a beveled gear 16 and engaging a bearing block 18 fitted to slide in a slot 20 in the lever. The crank gear is driven from the driving shaft 22 through a pinion 24 secured to the end of the shaft.

The die 26 for sizing and shaping the tubes to the mandrel and for polishing their outer surface is slightly smaller in diameter than the unfinished tube and is secured in the inner end of a hollow shaft 28 which is mounted in bearings 30 secured to the machine frame and so arranged that the die is in alignment with one of the mandrels carried by the turret. The die is rotated by a belt 32 passing over a pulley 34 on the die shaft and uniform rotation of the die during the full stroke of the turret is insured by a fly wheel 36 secured to the shaft.

A lubricant such as a suitable oil, grease or sizing is applied to the outer surface of the tube as it is about to enter the die by a lubricating device, which, as shown in Fig. 1, comprises a fountain brush 38 arranged in front of the die. The brush is carried by an arm 40 secured to one end of a rock shaft 42, the other end of which is provided with a second arm 44 connected by a link 46 with a lever 48. The end of the lever 48 is connected by a link 50 with the outer end of a lever 52, the inner end of which engages a cam 54 on a cam shaft 56. The cam shaft is driven from the driving shaft 22 through a gear 58 and pinion 60. The cam 54 is properly shaped to lift the lubricating brush as the rear end of the tube passes beneath it, to hold it in raised position during the return stroke of the mandrels, and to again return it into a position to apply the lubricant to the succeeding tube during the next forward stroke of the turret slide.

The lubricant is carried in a cylinder 62 and is forced downward through the brush by a screw threaded plunger 64 which is advanced step-by-step by a ratchet nut 66 engaged by a pawl 68. The pawl is carried by a lever 70 connected by a link 72 to the upper end of a fixed bar 74. Each time the brush is raised and lowered by rotation thereof about the rock shaft 42 as an axis, there will occur a relative movement between the pawl carrying lever and the ratchet nut, operating

100

105

110

the ratchet nut a step and thus advancing the screw threaded plunger. When the supply of lubricant in the cylinder 62 is exhausted, the plunger 64 may be screwed up to the upper end of the cylinder by hand and a fresh supply of lubricant forced into the cylinder under the plunger through a flexible pipe 76, the upper end of which is connected to a pipe 78 provided with a controlling valve 80 and the lower end of which is connected to a pump within the supply tank 82 which may be operated by the hand lever 84.

The means for feeding or automatically supplying tubes to the mandrel 4 which is out of alignment with the die and in tube receiving position, comprises tube feeding and supporting segments 86 secured upon a rock shaft 88 and provided with tube positioning notches 90. The segments are arranged at the lower delivery end of a hopper 92 within which the tubes to be treated are placed. The feed segments are oscillated to take a tube from the lower end of the hopper and present it in position to be entered by the mandrel during the forward stroke of the turret slide. The segments are thus oscillated by a cam on the cam shaft arranged to engage one end of a lever 94, the other end of which is connected by a link 96 with a three arm lever 98 which, in turn, is connected by a link 100 with an arm 102 on the segment shaft 88. The lever 98 is also connected by a link 104 with a tube agitator 106 arranged to act on the tubes within the hopper. The rear end of the hopper is provided with a projection 108 which lies back of the end of the tube when in position to receive the mandrel and holds the tube against endwise movement as the mandrel is pushed forward through it, a hole 110 being formed in the projection through which the end of the mandrel may pass.

Each mandrel is provided with a sleeve 112 for engaging the inner end of the tube and preventing its endwise movement on the mandrel as the forward end of the tube is thrust into the die. This sleeve is mounted on the mandrel so that it may have a limited endwise movement thereon to permit the mandrel to carry the rear end of the tube through the die. As shown, the sleeve is connected with the mandrel by a pin 114 passing through a slot 116 in the mandrel. The forward end of the slot is provided with an off-set 118 into which the pin may be turned to lock the sleeve in position. When the mandrel has received a tube and been brought into alignment with the die, as indicated in Figs. 1 and 2, the sleeve 112 is locked in forward position on the mandrel by engagement of the pin 114 with the off-set 118. As the rear end of the tube approaches the die, the outwardly project-

ing end of the pin rides up an inclined cam 120 which rocks the sleeve and swings the pin out of the off-set and then further forward movement of the sleeve is arrested by the engagement of the pin with a shoulder 122 at the end of the cam incline, as shown in Fig. 5. During the continued and final forward movement of the mandrel, the rear end of the tube is carried through the die and the sleeve moved back on the mandrel bringing the pin near the rear end of the slot 116, as indicated in Fig. 6. When this mandrel is moved into tube receiving position and is advanced through the tube held by the feed segments, the projecting end of the pin 114 rides over the end of a spring supported latch 124 and passes in front of a shoulder 126 on the latch, as indicated in Fig. 3. When the mandrel starts back, the sleeve 112 is held from movement by the engagement of the pin with the shoulder on the latch and the sleeve moves forward on the mandrel until it reaches the forward end of the slot 116 when its projecting end rides over the shoulder 126, thus rocking the sleeve and bringing the pin into the off-set 118 to lock the sleeve in position against the rear end of the tube.

The turret is indexed to shift the tube mandrels successively from tube receiving position to position in alignment with the die by an indexing shaft 128 provided on its forward end with a socket 130 arranged to receive the squared rear end 132 of the turret shaft. The squared end of the turret shaft enters the socket during the latter part of the retracting movement of the turret slide and continues in the socket until the end of a mandrel has entered or is about to enter the die. The indexing shaft is oscillated in the proper manner and at proper intervals through a segment 134 which engages a pinion 136 on the outer end of the index shaft. The segment is oscillated through a cam 138 secured on the cam shaft 56 and engaging a roll 140 on the segment.

When a tube is forced through the die by the advance movement of a mandrel, it is stripped from the mandrel during its return stroke by stripper fingers 142 mounted in the inner end of a delivery tube 144 which extends through the die shaft 28 and is supported in bearings 146. The stripper fingers are pressed inward by a surrounding coil spring 148.

In order that the tubes may be successfully delivered onto a conveyor such, for instance, as indicated at 150 in dotted lines in Fig. 1, the delivery tube is provided at a point beyond the outer bearing 146 with a lateral opening 152 through which the tubes may be discharged laterally onto the conveyor. The delivery tube is intermittently rocked to discharge the tubes through the

5 delivery opening by a cam 154 secured to the outer end of the cam shaft and engaging a lever 156 which is connected by a link 158 with a crank arm 160 on the delivery tube. The lever is held in engagement with the cam by a spring 162.

In Figure 9 another form of lubricating means is illustrated. As here shown, the lubricant is spread onto the tube by a spray nozzle indicated at 164. The nozzle is connected by a pipe 166 with an air supply and through a pipe 168 with a lubricant supply. The delivery of air and lubricant through the pipes is controlled by valves 170 which are opened and closed by a cam lever 172 connected with the valves through a link 174 and operated by a cam on the cam shaft corresponding to cam 54 of Fig. 1. The oil or other lubricant may be delivered to the pipe 168 from a supply tank 176 by a rotary pump 178, the delivery pipe of which communicates with the pipe 168 and is provided with a by-pass valve 180 for securing a supply under a fixed pressure.

25 While the machine shown and described embodies a simple and efficient form of the invention, it will be understood that the specific construction and arrangement of parts shown and described is not essential to 30 the broader features of the invention and may be varied or modified as found desirable or best suited to the condition under which the invention is to be utilized.

What is claimed is:

35 1. A machine for sizing or polishing tubes having, in combination, a revolving die, a tube carrying mandrel, a reciprocating carriage on which the mandrel is mounted, and an indexing mechanism for bringing the mandrel successively into position to receive a tube and into position in alignment with the die, said mechanism having provision for operative connection with the carriage when the mandrel is disengaged from the die and being adapted to be disconnected therefrom when the mandrel enters the die.

2. A machine for sizing or polishing tubes having, in combination, a revolving die, a reciprocating carrier provided with a plurality of tube carrying mandrels, and an indexing mechanism for shifting the carrier to bring the mandrels successively into position to receive a tube and into position in alignment with the die, said mechanism being adapted to be operatively connected with the carrier when the mandrels are disengaged from the die and to be disconnected therefrom when the carrier is moved to cause a mandrel to enter the die.

60 3. A machine for sizing or polishing tubes having, in combination, a turret provided with a plurality of tube carrying mandrels, a revolving die, a tube feeding mechanism, means for relatively reciprocating the turret and die, a stationary indexing

ing mechanism for bringing each mandrel successively into position to receive a tube from the feeding mechanism and into position to enter the die, and means connected with the turret for engaging the indexing mechanism when the mandrels are disengaged from the die and adapted to be disconnected therefrom when a mandrel enters the die.

4. A machine for sizing or polishing tubes having, in combination, a tube carrying mandrel, a revolving die, mechanism for relatively moving the mandrel and die to force a tube on the mandrel through the die, and lubricating means for the tube arranged in proximity to the mandrel only during the entrance of the tube into the die.

5. A machine for sizing or polishing tubes having, in combination, a tube carrying mandrel, a revolving die, mechanism for relatively reciprocating the mandrel and die, means for supplying a lubricant to the outer surface of the tube during the forward travel of the mandrel and tube through the die and for discontinuing the supply during the return travel of the mandrel.

6. A machine for sizing or polishing tubes having, in combination, a tube carrying mandrel, a revolving die, mechanism for relatively reciprocating the mandrel and die, means for supplying lubricant to the tube, and mechanism for rendering said means active during the travel of the mandrel and tube through the die and inactive during the withdrawal of the mandrel from the die.

7. A machine for sizing or polishing tubes having, in combination, a tube carrying mandrel, a revolving die, mechanism for relatively reciprocating the mandrel and die, a lubricating brush in front of the die, and means for raising and lowering the brush.

8. A machine for sizing or polishing tubes having, in combination, a tube carrying mandrel, a revolving die, mechanism for relatively reciprocating the mandrel and die, a sleeve mounted for limited end-wise movement on the mandrel, means for holding the sleeve in position on the mandrel to engage the rear end of the tube, and means for releasing the sleeve to permit the end of the tube to be carried through the die by the mandrel.

9. A machine for sizing or polishing tubes having, in combination, a tube carrying mandrel, a revolving die, mechanism for relatively reciprocating the mandrel and die, a sleeve mounted for limited end-wise movement on the mandrel, means for holding the sleeve against the thrust of a tube on the mandrel as the tube enters the die, and for thereafter moving the sleeve

125

130

away from the rear end of the tube to permit it to pass through the die with the mandrel.

10. A machine for sizing or polishing tubes having, in combination, a tube carrying mandrel, a revolving die, mechanism for relatively reciprocating the mandrel and die, means for stripping the tube from the mandrel during the return travel of the mandrel, and means for delivering the tubes laterally.

11. A machine for sizing or polishing tubes having, in combination, a tube carrying mandrel, a revolving die, mechanism for relatively reciprocating the mandrel and die, a delivery tube for receiving the

tubes passed through the die provided with a lateral delivery opening in its side, means for stripping the tubes from the mandrel, and mechanism for rocking the delivery 20 tube.

12. A machine for sizing or polishing tubes having, in combination, a tube carrying mandrel, a revolving die, mechanism for relatively reciprocating the mandrel 25 and die, a lubricating brush in front of the die, means for raising and lowering the brush, and means for supplying lubricant to the brush at each raising and lowering operation.

NORMAN MARSHALL.
